CLAIM

The ornamental design for an induction symphony light, as shown and described.

DESCRIPTION

FIG. 1 is a front, bottom, and right side perspective view of an induction symphony light, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front, top and left side perspective view thereof.

The broken lines in the drawings depict portions of the article and do not form part of the claimed design.

1 Claim, 8 Drawing Sheets
